UNITED STATES PATENT OFFICE.

JOHN T. TODD, OF SPRINGFIELD, ILLINOIS, ASSIGNOR TO THE REGISTERED TRACER SYSTEM, OF SPRINGFIELD, ILLINOIS, A CORPORATION OF ILLINOIS.

FILE AND BINDER.

1,120,864.

Specification of Letters Patent. Patented Dec. 15, 1914.

Application filed February 19, 1914. Serial No. 819,609.

To all whom it may concern:

Be it known that I, JOHN T. TODD, a citizen of the United States, residing at Springfield, in the county of Sangamon and State 5 of Illinois, have invented certain new and useful improvements in Files and Binders, of which the following is a specification.

This invention relates to improvements in files and binders, particularly adapted, 10 though not necessarily limited in its use for filing correspondence, and one of the objects of the invention is to provide an improved device of this character, constructed from a single sheet of material and cut in a single 15 operation, and then folded so that a portion of the blank will serve as a reinforce for the fold of the file, thereby adding strength and durability to the file, while another portion of the blank is folded to form one or more 20 inclosed tabs, to or between which, the correspondence may be removably secured.

A further object is to provide an improved device of this character having a back or edge which will open to accommodate 25 the growth of the contents of the file.

A further object is to provide an improved device of this character, having fastening devices for the correspondence, disposed entirely within the covers and also 30 having a flap connected with one of the covers, and which flap serves as a closure for the open edge of the file, to protect the edges of the papers.

To the attainment of these ends, and the 35 accomplishment of other new and useful objects as will appear, the invention consists in the features of novelty in substantially the construction, combination and arrangement of the several parts, hereinafter 40 more fully described and claimed, and shown in the accompanying drawings in which:

Figure 1 is a perspective view of a file of this character, constructed in accordance 45 with the principles of this invention, and as showing the bottom of the file. Fig. 2 is a perspective view of a portion of the blank, from which the file is cut, and showing the manner of cutting and scoring the blank. 50 Fig. 3 is an end elevation of a portion of the parts shown in Fig. 1 showing the position the parts will assume when a few papers are secured in the file. Fig. 4 is a view similar to Fig. 3 showing the position the parts

will assume when the file is expanded and a 55 number of papers are secured therein. Fig. 5 is a detail perspective view showing the manner of folding the blank shown in Fig. 2. Fig. 6 is a sectional view taken on line 6-6, Fig. 4. Fig. 7 is a view similar to 60 Fig. 1 of a modified form of the invention. Fig. 8 is a detail perspective view of a portion of the blank from which the file shown in Fig. 7 is constructed, and showing the manner of cutting and scoring the blank. 65 Fig. 9 is a section of a portion of Fig. 7, and on line 9-9. Fig. 10 is a detail perspective view showing the manner of folding the blank shown in Fig. 8. Fig. 11 is a detail perspective view of the file shown in Fig. 7, 70 with the file open.

Referring more particularly to the drawings, and in the form of the invention shown in Figs. 1 to 6, the numeral 15 designates a portion of a blank from which the file is 75 constructed, and which blank may be constructed of any suitable material, such as tough paper or the like, and may be of any desired size and configuration. The blank is cut intermediate its ends along the lines 80 16, 17 and also the lines 18, 19 as well as the lines 20, 21 and 22, 23 to form the tabs or ears 24, 25 adjacent the edges of the blank and the cuts 18 and 20 will result in the formation of connecting portions 26 extending 85 between one of the covers of the file and the portion 27, which forms the back of the file, while the cuts 19 and 21 form the connecting portions 28 between the other cover of the file and the back 27. The respective 90 cuts 18 and 20 extend from the cuts 16 and 22 and preferably converge toward each other and away from the cut 16, while the cuts 19 and 21 also preferably converge toward each other and away from the cut 17. While 95 these various cuts are being made in the blank, the blank is also scored along the lines 29, 30, 31, 32, 32^a and 33 for a purpose to be hereinafter set forth.

If desired and while the blank is being 100 cut and scored, it may also be perforated to form the apertures 35, 37, being formed through the respective connecting portions 26, 28, while the apertures 34, 36 are formed through the body of the blank, respectively 105 adjacent the apertures 35, 37. Slots 38, 39 may also be formed in the blank, respectively adjacent the apertures 34 and 36.

These cuts and perforations, together with the scoring of the blank, are arranged intermediate the extremities of the blank and in such a manner that the portion 40 (see particularly Fig. 1) which forms the bottom of the file, is somewhat shorter than the portion 41 forming the top of the file, so that the extremity 42 of the top of the file, which projects beyond the edge of the bottom of the file, may be folded to form a flap to lap over the back of the file for the purpose of protecting the edges of the papers.

The blank thus cut, scored and perforated, may be folded in any desired or suitable manner but preferably as follows: The outer face of the top of the file may be placed upon a support and the remaining portion of the blank then raised so that a portion of the back along the cuts 17 and 23 may be passed over the portion 43 and also over the ears 25, the connecting portions 28 during such folding operation folding on the lines 44, and being temporarily folded over and against the inner face of the top 41 of the file. The back 27 is then folded on the lines 27^a and the bottom of the file 40 is then again folded, so as to pass over the portion 45 of the back and over the ears 24, so that the connecting portions 26 will fold along the lines 46. This will cause the ears 24 to rest flat against the ears 25, and the portion 43 of the then upper face of the top 41 to rest flat against the lower face of the portion 45 of the back. The bottom of the file is then turned backwardly and along the lines 47 so as to extend over the portions 26 and the portions 43 and 45, and finally the bottom 40 is folded along the line 29. This will form two tabs designated generally by the reference numeral 48 in Figs. 3 and 6, which are arranged between the covers of the file and substantially parallel with each other. The parts thus folded may be secured together in any suitable manner, and the back 27 is creased along the lines 31, 32, so as to form a back which will be expandible to accommodate the growth of the contents of the file. When the blank is thus folded and the parts fastened together, the apertures 34, 35, 36 and 37 will register with each other so that a fastening device 49 may be passed therethrough and through the correspondence to secure the correspondence between the tabs 48. As shown this fastening device 49 is preferably in the form of a metallic strip, the bottom of which is arranged between the tabs 48 and the extremities 50 thereof pass through the registering apertures and then through slots in the tabs such as slots 38 or 39 to protect the ends of the fasteners, while the body portion of the fastener will pass through the other slots 38, or 39 for holding it against displacement. It will thus be manifest that not only an expandible file is produced, but one in which

the fold or joint will be reinforced, thereby adding to the strength and durability of the file.

In the form of the invention shown in Figs. 7 to 11, there is provided only a single tab within the file covers, and is particularly adapted for light correspondence. In this form of the invention, the blank 51 is cut in a similar manner along the lines 52, 53 and also along the lines 54, 55 to form the connecting portions 56, the ears 57 and the portion 58. It is also scored along the lines 59, 60 and 61. The blank thus cut and scored may be folded by preferably placing the top 62 of the file upon a support and then folding the blank so that the connecting portions 56 will fold along their respective portions of the line 61 and until the connecting portions 56 rest flat against the face of the top 62 as shown clearly in Fig. 10. This will cause the bottom 63 of the file to be folded over away from the portions 58 and the ears 57 of the top. The bottom is then folded along the lines 60, backwardly over the portion 58 and ears 57, and the bottom is then again folded forwardly along the line 59. The portions 57, 58 may be then folded along the line 61 so that they will lap over the outer face of the bottom of the file as shown in Fig. 7, the portions 57 and 58 being secured to the exposed face of the bottom of the file in any suitable manner. This manner of folding the blank will result in the formation of a projecting tab inside of the file, which is formed by the portion 64 of the blank and the connecting portions 56.

If desired, suitable fastening devices such as eyelets 65 may be provided for securing the portions 64, 65 together, and fastening devices 66 may be provided which pass through the eyelets and which latter fastening devices serve as means for securing the correspondence in the file. The cover 62 is also preferably provided with an extending portion 67 which forms a flap adapted to fold over the free end of the bottom 63 for protecting the papers. Thus it will be manifest that with this improved structure, letters will be secured within the file and in the form shown in Figs. 1 to 6, the back will expand to accommodate the growth of the contents, and in both forms, the fold of the file will be reinforced to increase the durability, and the fastening devices which secure the correspondence within the file will be completely housed within the file, so that there will be no projecting portions of the fastening devices to catch on other files or papers, thereby presenting smooth outside surfaces to the file.

While the preferred forms of the invention have been herein shown and described, it is to be understood that various changes may be made in the details of construction,

in the combination and arrangement of the several parts, and in the manner of cutting and folding the file, as well as in the fastening devices and in the manner of securing them in position, within the scope of the claims, and without departing from the spirit of this invention.

What is claimed as new is:—

1. A device of the character described, constructed from a single blank cut to form partially severed but connected sections, the blank being folded so that one face of one of the sections will rest against the face of the other section and with a portion of one section overlapping the adjacent portion of the other section and secured to the latter to reinforce the fold between the sections, and with an intermediate portion of the blank shaped to form a fly or tab between the said sections, and to which tab, sheets may be secured.
2. A device of the character described, constructed from a single blank cut to form two partially severed but connected sections, one of the sections being folded over the other section, the portion constituting the fold or hinge between the sections embodying a portion of one section folded over the edge of the other section and secured to the outer face of the latter, a portion of both of the sections being folded to form a tab or fly connected therewith adjacent the fold between the sections, and to which tab, sheets may be secured.
3. A folder of the character described, constructed from a single blank cut to form two partially severed sections having foldable connecting portions therebetween, said portions being folded to cause the adjacent cut edges of the blank to overlap, a portion of one of the said overlapping edges of one section being secured to the other section and extending over the back of the folder, and a portion of the other section coöperating with the said connecting portion to form a free tab or fly between the said sections, all of said parts being secured against unfolding.
4. A folder of the character described, constructed from a single blank cut to form two partially severed sections having foldable connecting portions therebetween, said portions being folded to cause the adjacent cut edges of the blank to overlap, a portion of one of the said overlapping edges of one section being secured to the other section and extending over the back of the folder, and a portion of the other section coöperating with the said connecting portions to form a plurality of tabs or flies between which sheets may be secured.
5. A folder of the character described, constructed from a single blank cut to form two partially severed sections having foldable connecting portions therebetween, said portions being folded to cause the adjacent cut edges of the blank to overlap, a portion of one of the said overlapping edges of one section being secured to the other section and extending over the back of the folder, and a portion of the other section coöperating with the said connecting portions to which sheets may be secured, and fastening devices carried by the said tabs for detachably securing sheets thereto.
6. A device of the character described, constructed from a single blank cut to form two partially severed sections having foldable connecting portions therebetween, said connecting portions being spaced from the peripheral edges of the blank, and adapted to be folded to cause the adjacent cut portions to overlap, portions of one section being secured to the other section and extending across the joint between the folded sections and on both sides of the said connecting portions, and a portion of the other section being folded to coöperate with the said connecting portions to form a tab.
7. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections, and secured to the remaining section to form a back, portions of the intermediate section and one of the other sections coöperating with the respective connecting portions to form tabs to which sheets may be secured.
8. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections and secured to the remaining section to form a back, portions of the intermediate section and one of the other sections coöperating with the respective connecting portions to form tabs to which sheets may be secured.
9. A device of the character described,

portions being folded to cause the adjacent cut edges of the blank to overlap, a portion of one of the said overlapping edges of one section being secured to the other section and extending over the back of the folder, and a portion of the other section coöperating with the said connecting portions to form a plurality of tabs or flies between which sheets may be secured, and fastening devices for securing sheets to the tabs.

75

6. A device of the character described, constructed from a single blank cut to form two partially severed sections having foldable connecting portions therebetween, said connecting portions being spaced from the peripheral edges of the blank, and adapted to be folded to cause the adjacent cut portions to overlap, portions of one section being secured to the other section and extending across the joint between the folded sections and on both sides of the said connecting portions, and a portion of the other section being folded to coöperate with the said connecting portions to form a tab.

80

7. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections, and secured to the remaining section to form a back, portions of the intermediate section and one of the other sections coöperating with the respective connecting portions to form tabs to which sheets may be secured.

85

8. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections and secured to the remaining section to form a back, portions of the intermediate section and one of the other sections coöperating with the respective connecting portions to form tabs to which sheets may be secured.

90

9. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections and secured to the remaining section to form a back, portions of the intermediate section and one of the other sections coöperating with the respective connecting portions to form tabs to which sheets may be secured.

95

10. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections and secured to the remaining section to form a back, portions of the intermediate section and one of the other sections coöperating with the respective connecting portions to form tabs to which sheets may be secured.

105

11. A device of the character described, constructed from a single blank and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections and secured to the remaining section to form a back, portions of the intermediate section and one of the other sections coöperating with the respective connecting portions to form tabs to which sheets may be secured, and fastening devices carried by the said tabs for detachably securing sheets thereto.

115

12. A device of the character described,

120

125

130

constructed from a single blank, and cut to form an intermediate section and two sections connected therewith by connecting portions, said portions being folded to cause the adjacent cut portion of one of the sections and of the intermediate section to overlap, and both to overlap the adjacent edge of the remaining section, to cause the cut edge of the last recited section, and one of the cut edges of the said intermediate section to be superposed, said superposed edges being secured together and bent over the space between the adjacent sections, and secured to the remaining section to form a back, portions of the intermediate section and one of the other sections coöperating with the respective connecting portions to form tabs to which sheets may be secured, and fastening devices carried by the said tabs for detachably securing sheets thereto, the said back being shaped to expand to compensate the growth of the contents.

10. A device of the character described,

constructed from a single blank cut to form two partially severed but connected sections, the blank being folded to cause the adjacent cut edges to overlap, a portion of the overlapping edge of one section being secured to the other section to form a hinge connecting the sections, said blank being also folded to form an integral tab or fly between the sections and adjacent the hinge and to which tab, sheets may be secured, the free edge of one section extending beyond the adjacent free edge of the other section and adapted to be folded thereover to form a closure flap.

In testimony whereof I have signed my name to this specification, in the presence of two subscribing witnesses, on this 10th day of February A. D. 1914.

JOHN T. TODD.
